UNITED STATES PATENT OFFICE.

JOHN H. HANLON, OF SOMERVILLE, MASSACHUSETTS.

DRIFTING VALVE.

1,423,797.

Specification of Letters Patent. Patented July 25, 1922.

Application filed October 24, 1917. Serial No. 198,217.

To all whom it may concern:

Be it known that I, JOHN H. HANLON, a citizen of the United States, residing at Somerville, county of Middlesex, State of

5 Massachusetts, have invented a certain new and useful Improvement in Drifting Valves, of which the following is a specification, reference being had therein to the accompanying drawings.

10 My invention has for its object a new and improved drifting valve for use on steam locomotives by which a supply of wet or saturated steam will be furnished to the working cylinders during the time when

15 the locomotive is in motion but is not being supplied with steam through the dry pipe. As is well understood by those skilled in the

art, the use of superheaters on steam locomotives has resulted in certain difficulties which 20 it is the purpose of so-called drifting valves to overcome. For instance, the temperature of the cylinder walls as a result of the use of superheated steam is so high that when the throttle is closed, the cylinder and piston

25 are practically without lubrication so that the packing is quickly destroyed or the cylinders scored. The air drawn into the cylinders by the suction of the pistons contains dust, which together with the oil burns or 30 "carbonizes" as it is termed and injury is done to the parts. The carbonization which takes place builds up a layer on the piston head and walls of the valve chamber reducing the clearance and causing the engine to

35 knock, interfering with its proper operation and with the removal of the parts. Accordingly it is desirable to supply saturated steam to the cylinders in sufficient quantities to lubricate the walls of the cylinders at

40 such times as the locomotive is moving and the supply of superheated steam is shut off. The drifting valve embodying my invention is so constructed that saturated steam is sent to the cylinders whenever the engineer

45 closes the throttle valve and the flow continues as long as the locomotive is in motion and stops automatically when the locomotive stops. Provision is made so that there is no possibility of steam pressure building up in

50 the cylinders of the locomotive and moving the locomotive in case the engineer fails to give the apparatus its proper attention. The apparatus is wholly automatic and requires no attention whatever aside from oiling.

55 The invention will be fully understood when taken in connection with the follow-

ing description and accompanying drawings and the novel features thereof will be pointed out and clearly defined in the claims at the close of this specification.

60

In the drawings, Fig. 1 is a side elevation of a locomotive to which is applied a drifting valve embodying my invention.

Fig. 2 is a vertical section on line 2—2 of Fig. 1 on an enlarged scale.

65

Fig. 3 is a section on line 3—3 of Fig. 2.

Fig. 4 is a view similar to that shown in Fig. 2 but with the parts in a different position.

Fig. 5 is a view showing the position of the parts after the trip cylinder has operated.

Fig. 6 is a detail of the main valve member.

Fig. 7 is a section on line 7—7 of Fig. 6.

Fig. 8 is a top plan view of the plunger 22.

75

Referring now to the drawings and particularly to Fig. 1 at A is shown the ordinary throttle valve of the locomotive, being operated by the hand lever B and connecting rod C. At D is shown a bracket by means of 80 which is supported the apparatus embodying my invention and which for convenience is termed the drifting valve. At 11 is shown a pipe leading to the interior of the locomotive boiler as for instance through a steam dome 12. At 13, 13 are shown two branch pipes leading 85 to the locomotive cylinders. The three pipes are connected by a valve casing 14 within which is located a balanced main valve 15 (see particularly Fig. 6.) This balanced 90 valve 15 has a valve member *a* which engages a seat *b*. The valve is also provided with a stem *c* and piston *d* adapted to operate in a cylindrical bore formed at *e* in the lower part of the casing 14. It will be seen that when the valve member *a* is off its seat *b*, as shown in Fig. 4, the pipe 11 is connected with the two pipes 13, 13 so that saturated steam can flow through them to the cylinders of the locomotive. The valve member 15 is 100 bored longitudinally to receive an auxiliary valve 16 the stem of which is of substantially triangular cross section as shown in Fig. 7. The stem 16 protrudes below the lower end of the main valve 15 and terminates in a 105 head 17. The upper end is provided with a conical valve member 18 engaging a seat *f* which is formed in the main valve member. At 20 is shown a small port through the piston *d* to prevent steam from accumulating 110 under the piston *d* of the main valve 15. It will be seen that the construction is such

that when the auxiliary valve 16 is lifted steam can pass through the bore of the main valve and under its lower end thereby largely counterbalancing the pressure on the upper 5 side of the main valve and making it possible to lift the main valve with a minimum effort.

Guided in the stuffing box 21 secured to the casing 14 is a plunger 22 adapted to be 10 moved vertically and to engage the lower end of the auxiliary valve 16 and the main valve 15. The upper face of the plunger is grooved as shown at 19 (see Figs. 2 and 8) to permit steam to flow beneath the main 15 valve 15 when the plunger and main valve are in contact. This plunger is moved vertically by a cam 23 which is rotatable on a rod 24, said rod being slidable in a bracket 30 by which the trip cylinder 31 and main valve 20 casing 14 are supported. The lower end of the cam is provided with a tail *g* located in the path of the throttle lever B. For convenience of adjustment the contact between the throttle lever B and the tail of the cam 25 23 may be regulated by means of a screw pin 25 and check nut 26. Surrounding the rod 24 is an open spiral spring 27 one end of which contacts with the pin 28 on the bracket 30 and the other end of which enters a hole 30 29 in the cam 23. The spring 27 performs two functions, first that of rotating the cam 23 on the rod 24 in a direction opposite to that which the throttle lever rotates the cam 23, and second, to push the cam 23 and attached parts as far to the left as shown in Fig. 2 as possible.

Secured to the bracket 30 which supports the device is a trip cylinder 31 containing the piston 32 secured to a stem 33 which acts 40 on the cam 23 to slide it with the rod 24. One end of the trip cylinder is connected by a pipe 34 to a port 35 which intercepts the main port of the main valve. The amount of opening of said port 35 may be adjusted 45 by means of a needle valve 36 enclosed within the cap 37. This needle valve 36 regulates the amount of steam which can flow from the main valve to the trip cylinder 31 and therefore the length of time which will 50 elapse before the trip cylinder will act to move the cam 23 to the right. At 38 is shown a bleed port through which the steam in the trip cylinder is exhausted after the trip cylinder has been actuated.

At 39 and 40 is shown a by-pass around the main valve seat and this by-pass is opened or closed by the valve 41 operated by the handle 42. An alarm port 43 leads out through the stem of this valve and gives 55 warning by the emission of steam whenever the valve is left open. By opening this valve the engineer can permit a small quantity of steam to pass to the cylinders of the locomotive when the locomotive is standing still even though the drifting valve is closed.

This is advantageous because it makes it possible to admit live steam to the cylinders to warm them up or to blow out any accumulation of condensation.

The operation of the drifting valve embodying my invention is as follows: Under normal conditions when the locomotive is standing still or is running with the throttle open, the drifting valve is closed. When the engineer closes the throttle, the throttle lever engages the pin 25 on the tail *g* of the cam 23 and swings the cam about its centre moving up the plunger 22 and first lifting the auxiliary valve 16 and then the main valve 15. When the main valve is lifted, 70 the steam flows from the pipe 11 to each of the cylinder pipes 13. At the same time, steam is free to flow through the port 35 and pipe 34 to the trip cylinder 31 but no pressure accumulates in the trip cylinder because the suction produced by the locomotive cylinders when the locomotive is running with closed throttle is so great that the small supply of steam entering through the pipe 11 does not produce any appreciable pressure. If the engineer opens the throttle again before the locomotive comes to a stop, the operation of the drifting valve ceases because the movement of the throttle lever permits the pressure on the main steam valve 75 to push the main steam valve down causing the cam 23 to swing on its axis and to return to its former position. The movement of the cam 20 to its original position is caused in part by the curvature of the cam, and in part 80 by the spring 27 which is constructed to rotate the cam about its axis as well as to move it axially. If, however, the locomotive comes to a stop so that the suction in the cylinders ceases, pressure is immediately 85 communicated through the port 35 and pipe 34 to the trip cylinder 31 and this forces the piston 32 to the right from the position shown in Fig. 2. The movement of the piston 32 to the right moves the cam 23 out 90 from under the plunger 22 as shown in Fig. 5 compressing the spring 27. As soon as the cam 23 is moved out from under the plunger 22 the main valve closes shutting off the supply of saturated steam to the locomotive cylinders. There is, therefore, no possibility 95 of pressure building up while the locomotive is standing. The pressure in the trip cylinder immediately leaks out through the bleed port 38 and the spring 27 pushes the cam 100 23 and piston 32 back to the left until the cam 23 strikes the side of the plunger 22 as shown in Fig. 5. The parts remain in this position until the engineer begins to open the throttle. The spring 27 causes the cam 105 to rotate and follow the throttle lever until the cam has moved far enough so that the spring can push it under the end of the plunger. The parts are then set ready to 110 repeat the operation.

What I claim is:

1. In a device of the character described, a casing containing a main valve, a main valve, connections from the boiler to the 5 casing and from the casing to the cylinders of the locomotive and connections being controlled by said main valve, a trip cylinder operatively connected with said main valve, steam connections from the main valve to the trip cylinder and throttle operated 10 means for opening the main valve by the closing movement of the throttle.
2. In a device of the character described, a main valve controlling a steam passage 15 leading from the boiler to the cylinders of the locomotive, throttle actuated mechanism to open said main valve by the movement which closes the throttle, a trip cylinder operatively connected with the main valve 20 and connections from said steam passage to said trip cylinder whereby an accumulation of pressure in the cylinders of the locomotive will produce pressure in the trip cylinder and actuate it to permit the closing of 25 the main valve.
3. In a device of the character described, and in combination with a boiler throttle and working cylinders of a locomotive, a steam passage leading from the boiler to 30 the cylinders, a main steam valve controlling said steam passage, mechanism actuated by the throttle valve to open said main valve, a trip cylinder and piston acting on 35 said mechanism to permit the closing of said main valve and connections from the main valve to the trip cylinder so that pressure will accumulate in said trip cylinder whenever the main valve is open and the suction produced by the locomotive cylinders 40 is not sufficient to relieve the pressure produced by the flow of steam through the main valve.
4. In a device of the character described, and in combination with a boiler throttle 45 and the working cylinders of a locomotive, a steam passage leading from the boiler to the cylinders, a main steam valve controlling said main steam passage, said main steam valve having a valve plunger, a cam 50 engaging said valve plunger and actuated by the throttle of the locomotive, a trip cylinder and piston acting on said cam to move it out of operative relation with said plunger and connections from the main 55 valve to the trip cylinder so that pressure will accumulate in said trip cylinder whenever the main valve is open and the suction produced by the locomotive cylinder is 60 not sufficient to relieve the pressure produced by the flow of steam through the main valve.
5. In a device of the character described, and in combination with a boiler throttle 65 and the working cylinders of a locomotive, a steam passage leading from the boiler to
- the cylinders, a main steam valve controlling said main steam passage, said main steam valve having a valve plunger, a cam engaging said valve plunger and actuated by the throttle of the locomotive, said cam 70 being mounted to rotate and slide, a trip cylinder and piston acting on said cam to slide it out of operative relation with said plunger, and connections from the main valve to the trip cylinder so that pressure 75 will accumulate in said trip cylinder whenever the main valve is open and the suction produced by the locomotive cylinders is not sufficient to relieve the pressure produced by the flow of steam through the main 80 valve.
6. In a device of the character described, a main valve controlling a steam passage leading from the boiler to the cylinders of a locomotive, throttle actuated mechanism 85 to open said main valve by movement which closes the throttle, a trip cylinder and piston acting on said mechanism to permit the closing of said main valve, connections from the main valve to the trip cylinder so that 90 pressure will accumulate in said trip cylinder whenever the main valve is open and the suction produced by the locomotive cylinders is not sufficient to relieve the pressure produced by the flow of steam through the main valve, and a needle valve in said connections between the main valve and the trip cylinder whereby the rate of flow of steam to the trip cylinder may be varied.
7. In a device of the character described, a casing containing a main valve, a main valve, connections from the boiler to the casing and from the casing to the cylinders of the locomotive said connections being controlled by said main valve, a trip cylinder operatively connected with said main valve, steam connections from said main valve to the trip cylinder, throttle operated 100 means for opening the main valve by the closing of the throttle, an auxiliary valve 105 in said main valve, said auxiliary valve having a stem for engagement with said throttle operated means so that the auxiliary valve is opened in advance of the opening of the main valve.
8. In a device of the character described, a casing containing a main valve, a main valve, connections from the boiler to the casing and from the casing to the cylinders of the locomotive said connections being 110 controlled by said main valve, a trip cylinder operatively connected with said main valve, steam connections from the main valve to the trip cylinder, throttle operated means for opening the main valve by the closing movement of the throttle, and a bypass about said main valve to admit steam directly to the cylinders.
9. In a device of the character described, a casing containing a main valve, a main 115

valve, connections from the boiler to the casing and from the casing to the cylinders of the locomotive said connections being controlled by said main valve, a trip cylinder 5 operatively connected with said main valve, steam connections from the main valve to the trip cylinder, throttle operated means for opening the main valve by the closing movement of the throttle, and a hand-controlled by-pass about said main valve to admit steam directly to the cylinders.

10. In a device of the character described, in combination, a valve for controlling the flow of steam to the cylinders of a locomotive, means for opening said valve, and a trip cylinder and piston controlled by the pressure in the locomotive cylinders when said valve is open for acting on said opening means to permit said valve to close, said 15 device having provision, controlled by a part of the locomotive which is moved in starting the locomotive, for rendering said opening means inoperative to open said valve until the locomotive is started after having 20 stopped.

11. In a device of the character described, in combination, a valve for controlling the flow of steam to the cylinders of a locomotive, means for opening said valve, and a trip cylinder and piston controlled by the 30 pressure in the locomotive cylinders when said valve is open for rendering said opening means inoperative and thereby permitting said valve to close when the locomotive stops, said opening means being controlled by some part of the locomotive which is moved in starting the locomotive and being prevented thereby from returning to operative position until the locomotive is started, 35

12. In a device of the character described, 40 a steam passage leading from the boiler to the cylinders of the locomotive, a main valve controlling said passage, throttle operated means to cause a movement of the main valve in one direction, and a trip cylinder 45 subjected to steam pressure from the cylinders of the locomotive to cause a movement of the main valve in the other direction.

In testimony whereof I affix my signature,
JOHN H. HANLON.
